PREWELT SHAPING MACHINE

Carl George Deubel, St. Louis, Mo., assignor to
Progressive Service Company, St. Louis, Mo., a
corporation of Missouri

Application March 29, 1933, Serial No. 663,314

21 Claims. (Cl. 12—7)

This invention relates to pre-welt shaping machines, and an object of the invention is to provide a machine for shaping pre-welt shoe uppers in which a welt is attached to the shoe upper before lasting.

Another object of the invention is to provide a machine for shaping a pre-welt shoe upper on and about a last without cutting, puncturing or tearing the shoe upper or the welt and, at the same time, eliminate those operations heretofore required and designated or described under the terms side lasting, toe lasting, seat lasting, tacking, tack pulling, welt beating and sole laying.

Another object of the invention is to provide an improved pre-welt shaping machine for shaping a pre-welt shoe upper on and about a last with much greater nicety and precision than is possible by use of plates or similar elements to engage the shoe upper immediately adjacent to the welt in order to press and shape the shoe upper on and about the last. The plates and similar element are substantially inflexible in the plane in which they apply pressure, so that any thickened or folded or creased portions of the shoe upper engaged by the pressure edges of the plates or similar elements, or that become engaged between the plates or similar elements, are likely to be cut, punctured or torn, or otherwise damaged, when said plates or similar elements are operated to apply pressure to and against the shoe upper to shape the same on and about the last.

Another object of the invention is to provide flexible members for shaping the toe and heel portions or a pre-welt shoe upper on and about a shoe last in order to avoid cutting, puncturing and tearing the shoe upper or subjecting any portions thereof to undue strains and stresses and to provide additional means for shaping the side portions of the shoe upper in conformity with the last.

While the pre-welt shoe upper is held on and about the last, a cork or other composition insert is applied to cover the exposed surface of the last and to fill the space enclosed within the marginal portion of the shoe upper and welt. Next, and without the necessity of withdrawing tacks or other similar operations and without delayed operations such as are required by old methods, the sole is applied and adhesively secured to the welt and the filler. By this invention, I am enabled to use this improved method and process and avoid the necessary delay of several hours heretofore required to complete the shoe. This is because by the old methods of making this type of

shoe in which the upper was tacked to the last, it was necessary to keep the shoe upper on the last for several hours after the filler had been applied and before the remaining finishing operations could be performed.

Other objects of the invention should be readily apparent from the following description, reference being made to the annexed drawings, in which—

Fig. 1 is a perspective view, with the pedestal or supporting frame broken away, showing my improved pre-welt shaping machine with a shoe mounted therein ready to be shaped on and about the last.

Fig. 2 is a similar perspective view, the shoe being omitted.

Fig. 3 is a sectional view showing the pivoted supports for the side shaping members and the devices for accommodating the machine to support and shape shoes of different sizes.

Fig. 4 is a detail view showing the connections for operating the side shaping members.

Fig. 5 is a sectional view on the line 5—5 of Fig. 3.

Fig. 6 is an enlarged sectional view of the device for adjusting the last pin in position to support selected sizes of lasts.

Fig. 7 is a plan view of the gage device that cooperates with the last pin.

The machine comprises a rigid upright member 1 having a frame attached to its upper end. In the embodiment of the invention illustrated, the frame that is attached to the upper end of the upright member 1 comprises two side members 2 and 3 and a socket member 4 rigidly connecting said side members 2 and 3. This socket member 4 receives the upwardly extended part 5 rigid with the member 1. A clamping set screw 6 is screwed into a hole in the socket member 4 and clamps against the upwardly extended part 5 and constitutes means for holding the frame 2 in rigid location on the upper end of the member 1. This set screw 6 may be loosened or removed to permit removal of the frame 2—3 in order to facilitate and expedite the making of repairs on any of the parts and also the substitution of other or different frames in the place of the frame that is removed.

Further, the side members 2—3 of this frame, which are spaced apart, are shown as connected at their ends with rigid connecting members 7. Downwardly and outwardly inclined supports 8 are mounted in the connecting members 7. Blocks 9 are mounted adjacent to the inner upper ends of the supports 8 and seat upon the upwardly

5

55

converging surfaces of the socket member 4 and are guided between and held from lateral displacement by the frame members 2 and 3.

The inner upper end portion of each of the supports 8 is formed with a circumferential groove 10. A yoke is engaged in each of the grooves 10. As shown, each of said yokes comprises a pair of blocks 11 having matching edges and also having rounded notches intermediate of their ends. The lower blocks 11 slide along the inclined upper surfaces of the socket member 4 and the upper blocks are seated on the lower blocks. Screws 13 pass through the blocks 11 and engage in the adjacent block 9 and hold 10 and move said blocks in connection and along with the yoke comprising the blocks 11. A plate 14, having gage indicia on its upper surface and also having a longitudinal slot, is attached to the frame members 2 and 3 by removable and replaceable screws 15 and constitutes a guide for the upper sides of the blocks 9 and 11. Since the blocks 11 engage in the grooves 10, it is clear that said blocks 11 cannot move longitudinally along the supports 8 but that said supports 8 are free to rotate with respect to said blocks 11. Since the blocks 11 are attached to the blocks 9 by the screws 13, said blocks 9 will be moved along with the blocks 11 and the supports 8 are free to turn in said blocks 9. The supports 8 are threaded and are screwed in threaded holes in the connections 7 and are equipped on their outer ends with handles 8a, whereby said supports may be turned in either direction and thereby moved longitudinally in order to move the blocks 9 upwardly or downwardly along the inclined surfaces of the upper side of the connecting socket 4.

A last pin 16 is removably screwed into and extends vertically from the block 9 that is under the gage plate 14 and is adapted to be extended into the usual last socket in order to support the last in position for operation of this machine. The block 9 at the gage plate 14 has a pointer cooperating with said gage to facilitate adjustment of the last pin for lasts of different sizes. A supporting pin 17 extends vertically from the other block 9 and has mounted on its upper end an elastic pad 18 constituting a support for the toe portion of the shoe upper that is mounted 50 on the last and which last is mounted on the upper end of the last pin 16.

An angular lever 19 is mounted between lugs 20 formed rigid with the frame member 2 and has rigid with its upper end spaced arms 21. A shaping plate 22, having its inner edge 23 appropriately formed and shaped and curved in conformity with the shape which is to be given to that part of the lower portion of the pre-welt shoe upper extending forwardly from the forward part of the heel portion of the shoe upper at one side of the shoe, is attached to the arms 21. This should be understood by reference to Fig. 1 of the drawings considered in connection with well known facts. As shown in Fig. 1, the last 24 is mounted on the last pin 16 and a pre-welt shoe upper 25 is mounted on and about said last and has the welt 26 attached thereto. This welt 26 is attached to the upper before the upper is placed on the last. Stitches 27 constitute appropriate attaching means for attaching the welt 26 to the shoe upper 25. As shown, and as is well known, the lower portion of the shoe upper including the welt 26 must be curved inwardly at the sides of the shoe upper from the heel portion 70 of the shoe upper and thence outwardly. 75

The edge 23 of the plate 22 is appropriately shaped and formed to shape one side of this pre-welt shoe upper in conformity with this requirement. However, this plate 22 does not engage the shoe upper at any point rearwardly beyond the beginning of the curvature of the heel portion of the upper from one side to the other. Nor does this plate 22 engage the shoe upper at any point beyond the beginning of the curvature of the shoe upper from one side to the other thereof. 10

The plate 22 is attached to the upper ends of the arms 21 by removable and replaceable fastener screws 28. This easily permits removal of a plate 22 designed and intended for shaping shoes of one size, or of approximately the same 15 size, or within a range of sizes, and the substitution therefor of another plate for different styles or sizes of shoes.

An angular lever 29, similar to the angular lever 19, is mounted between spaced lugs 30 rigid with the frame member 3 and has upwardly extended arms 31. A shaping plate 32, having its inner edge 33 appropriately formed and shaped and curved in conformity with the shape which is to be given to that part of the lower portion of the 25 pre-welt shoe upper extending forwardly from the forward part of the heel portion of the shoe upper at one side of the shoe, is attached to the arms 31. This should be understood by reference to Fig. 1 of the drawings considered in connection 30 with the well known facts, as indicated in the preceding description in respect of the plate 22. Like the plate 22, the plate 32 does not engage the shoe upper at any point beyond the beginning of the curvature of the shoe upper from one side to the other either at the heel portion or at the toe portion of the shoe portion. This plate 32 is attached to the upper ends of the arms 31 by removable and replaceable screw fasteners 34. This easily permits removal of a plate 32 designed 40 and intended for shaping shoes of one size, or of approximately the same size, or within a range of sizes, and the substitution therefor of another plate for different styles or sizes of shoes. 35

The lever 29 is pivoted on a pivot 35 supported by the lugs 30 and the lever 19 is pivoted on a similar pivot supported by the lugs 20. These pivots are easily removable and replaceable in order to permit removal and replacement of the levers 19 and 29. 50

A lever 36 has one end mounted on a pivot 37 attached to a supporting bracket 38. The supporting bracket 38 is secured to the member 1 by a removable and replaceable fastener 39. A bracket 40 rigid with the member 1 is also attached to the bracket 38 by a removable and replaceable fastener 41. A vertical slot 42 in the bracket 38 opens into a vertical channel 43 in the member 1. A block 44 is mounted for vertical sliding movements in the slots 42 and 43 and supports a pivot 45 in the lever 36. One end of a link 47 is pivoted to the pivot 45 and the other end of said link 47 is connected with the lower end of the angular lever 29 by a pivot 48. A link 49 has one end connected by a pivot 50 with the block 44 and the opposite end connected by a pivot 51 with the lower end of the angular lever 19. An arcuate rack 52 is concentric with the axis of the pivot 37 and is formed on the bracket 38. A pawl 53, pivoted on the lever 36, is actuated into engagement with the rack 52 by a spring 54. An extension 55 in connection with the pawl 53 constitutes means whereby said pawl 53 may easily be operated out of engagement with the rack 52. 75

It is now clear that a handle 56, in connection with the free end of the lever 36, constitutes manually engageable means whereby said lever 36 may be moved upwardly and that such upward movement of said lever 36 will move the block 44 upwardly. Upward movement of the block 44 moves upwardly the ends of the links 47 and 49 that are pivoted to said block. This movement of the links 47 and 49 moves the lower ends of the angular levers 19 and 29 outwardly and upwardly and swings the shaping plates 22 and 32 inwardly from the spread apart position, shown in Fig. 2 of the drawings, to the effective shaping position shown in Fig. 1. The pawl 53, engaging the rack 52, will support the lever 36 in any of its adjusted positions and will hold the shaping plates 22 and 32 in the position shown in Fig. 1. To release the shaping plates 22 and 32 from shaping position, it is only necessary to engage and operate the extension 55 in opposition to the pressure of the spring 54. When the pawl 53 is moved out of engagement with the rack 52, the lever 36 may be swung downwardly, thereby moving the links 47 and 49 and operating the angular levers 19 and 29.

An angular lever, comprising a downwardly extended arm 57 and an upwardly extended arm 58, is mounted on a removable and replaceable pivot 59 supported by one end of the frame 2-3. A bracket 60 is attached to the upper end of the upwardly extended arm 58 by a removable and replaceable fastener 61 and has attached thereto in spaced relationship the ends of a flexible shaping member 62, which may be a metallic wire.

An angular lever, consisting of an outwardly extended arm 63 and an upwardly extended arm 64, is mounted on a removable and replaceable pivot 65 at the opposite end of the frame 2-3 from the pivot 59. A bracket 66 is attached to the upper end of the upwardly extended arm 64 by a removable and replaceable fastener 67, and the ends of a flexible shaping member 68 are attached thereto in spaced relationship.

The closed ends of the loop-like flexible shaping members 62 and 68 are adjacent to the upwardly extended lever arms 64 and 58, respectively, and the side portions of said loop-like shaping members 62 and 68 extend below the shaping members 22 and 32.

This arrangement permits the easy mounting on the last pin 16 of the last 24 having thereon the pre-welt shoe upper 25 with the welt 26 attached thereto. When so applied, the toe portion of the shoe upper rests on the pad 18, so that the last on which the shoe upper is mounted is substantially rigid.

Flexible connections 69, including turn-buckle devices 70 in connection therewith, have their upper ends connected with clips 71 mounted on pivots 72 supported by the outer ends of the lever arms 57 and 63, respectively. These turn-buckle devices function in the usual way and are operative to shorten or extend the combined length of the connected parts of the flexible connections 69. These flexible connections 69 extend downwardly and inwardly against rollers 73 mounted on axle members 74 supported by a bracket 75 attached to the upright member 1.

The upright member 1 is rigid with a base 76 which may be secured to any suitable support. In the arrangement shown, the base 76 is seated on a supporting table or plate 77 mounted on the upper end of a supporting frame 78. The base 76 and table 77 are attached to the upper end

of the supporting frame 78 by removable and replaceable fasteners 79.

The frame 78 may be a hollow frame, as clearly shown in Fig. 1. The flexible connections 69 extend downwardly through slots 80 in the base 76 and table 77 and thence downwardly into the hollow frame 78 and have their lower ends attached to a cross head 81 enclosed within the frame 78. The cross head 81 is pivoted to a lever 82 having one end mounted on a pivot 83 within the frame 78. The lever 82 projects outwardly through a slot 84 in the frame 78 and has a pedal 85 in connection with its outer end, whereby said lever 82 may be easily operated downwardly as required to operate the connections 69 and the levers with which said connections cooperate.

Springs 86 engage the pivots 59 and 65 and the pivots 72 and operate by their resiliency to raise the outer ends of the lever arms 57 and 63 when the operator releases the lever 82. Raising of the lever arms 52 and 63 moves the lever arms 58 and 64 inwardly toward each other and thus release the flexible shaping devices 62 and 68 from tight engagement with the pre-welt shoe upper.

In operation of this machine, the last 24, having thereon the pre-welt shoe upper 25 with the welt 26 attached thereto, is mounted on the last pin 16, the toe portion of the last and the shoe upper thereon extending over the pad 18 upon which the toe portion of the shoe upper seats. After the shoe has been properly applied in this way, the handle 56 is engaged and moved upwardly, thereby operating the lever 36 and moving the shaping plates 22 and 32 inwardly to engage the adjacent portion of the shoe upper at opposite sides of the last 24. The welt 26 extends above the shaping plates 22 and 32 and said plates do not engage the shoe upper or the welt beyond the beginning of the curved portions thereof at the heel or toe of the shoe upper. This operation of these shaping devices 22 and 32 properly shapes the two side portions of the shoe upper and said shaping devices will be held in effective position by the pawl 53 engaging the rack 52.

Next, the free ends of the flexible shaping devices 62 and 68 are raised so that they will engage the toe and heel portions of the shoe upper immediately adjacent to the welt 26. Then the lever 82 is operated to move the connections 69 downwardly and to swing the lever arms 57 and 63 downwardly. This moves the upwardly extended lever arms 58 and 64 outwardly and causes the flexible shaping devices 62 and 68 to engage the curved toe and heel portions of the shoe upper immediately adjacent to the welt 26 and to shape and hold the shoe upper in proper form and shape.

Then, the cork or other filler is placed in a plastic condition within the space surrounded by the welt 26 and smoothed. A sufficient time after the filler composition has been placed within the space surrounded by the welt 26 and smoothed, the shoe sole is adhesively united to said filler and to the welt. This may be effected by placing a coating of glue, adhesive cement, or other binding adhesive substance, on the exposed surface of the filler and the welt and then placing the sole in proper position thereon. After the adhesive binding substance dries, the shaping devices may be released and the shoe removed from the machine for any further finishing operations.

It must now be clear that my invention ob-

tains all of its intended objects and purposes and functions in a highly efficient manner to produce a nicer and better finished shoe than is possible by the use of machines subject to any of the 5 objections indicated in this specification or other objections. The shoe is not damaged, cut, punctured, or torn in any way by this machine, but is shaped with greater precision and rapidity than is possible by other machines or by manual operations. This eliminates and saves about one 10 day in the manufacture of pre-welt shoes in comparison with manual methods of shaping.

This machine may be varied within the full 15 scope of equivalent limits without departure from the nature and principle thereof. I contemplate such variations as may be desired to adapt the invention to all of the uses for which it is intended or other uses which may hereafter become known, and do not restrict myself in these particulars.

20 I claim:

1. A pre-welt shaping machine comprising a support for a pre-welt shoe upper, shaping members for the side portions of the shoe upper at the welt, mechanism for operating said shaping members to shape the side portions of the shoe upper at the welt, and flexible shaping means for shaping the curved end portions of the shoe upper at the welt between the portions of the shoe upper that are shaped by said shaping members.

30 2. A pre-welt shaping machine comprising supporting means for a pre-welt shoe upper, shaping members operative to shape the curved side portions of the shoe upper at the welt and terminating short of the front and rear curved 35 portions of the shoe upper, flexible shaping devices operative to engage and shape the curved end portions of the shoe upper at the welt, and means for operating said shaping members and said shaping devices respectively.

40 3. A pre-welt shaping machine comprising a support for a pre-welt shoe upper, flexible shaping devices for shaping the curved end portions of the shoe upper at the welt, and substantially inflexible shaping members operative between 45 said shaping devices and the welt to shape the inwardly curvd side portions of the shoe upper.

4. A pre-welt shaping machine comprising a last pin for engaging and supporting a last having thereon a pre-welt shoe upper, an element 50 for supporting the toe portion of the shoe upper and the last, means for adjusting and holding said last pin and said element in position to support lasts and shoe uppers of different sizes, flexible shaping devices for shaping 55 the curved end portions of the shoe upper at the welt, and substantially inflexible shaping members for engaging and shaping the side portions of the shoe upper between said shaping devices and said welt.

60 5. A pre-welt shaping machine comprising a last pin for engaging and supporting a last having thereon a pre-welt shoe upper, an element 65 for supporting the toe portion of the shoe upper and the last, means for adjusting and holding said last pin and said element in position to support lasts and shoe uppers of different sizes, flexible shaping devices for shaping the curved 70 end portions of the shoe upper at the welt, substantially inflexible shaping members for engaging and shaping the side portions of the shoe upper between said shaping devices and said welt, mechanism for operating said flexible shaping devices, and other means for operating said shaping members.

75 6. A pre-welt shaping machine comprising

flexible shaping devices for shaping the end portions of a pre-welt shoe upper at the welt simultaneously, and substantially inflexible shaping members operative to engage and shape the inwardly curved side portions of the shoe upper at the welt between said shaping devices and said welt.

7. A pre-welt shaping machine comprising 10 supporting means for a pre-welt shoe upper, shaping members having curved inner edges operative at the sides of the shoe upper to shape the curved side portions of the shoe upper at the welt, means for holding said shaping members in operated position to hold the curved side portions of the shoe upper properly shaped, and 15 flexible shaping means operative to engage and shape the curved end portions of the shoe upper at the welt beyond and between the ends of said shaping members.

8. A pre-welt shaping machine comprising 20 supporting means for a pre-welt shoe upper, flexible devices arranged to engage the curved end portions of the shoe upper at the welt, mechanism for operating said devices simultaneously, and substantially inflexible shaping members operative to engage and shape the inwardly curved 25 side portions of the shoe upper at the welt.

9. A pre-welt shaping machine comprising a 30 pair of spaced levers, means for supporting a pre-welt shoe upper between said levers, a flexible loop device having its ends attached to each lever and having its intermediate curved portion adapted to engage and shape the curved end 35 portions of the shoe upper at the welt opposite from said lever, and mechanism for operating said levers.

10. A pre-welt shaping machine comprising a support for a pre-welt shoe upper, flexible shaping devices having curved portions for simultaneously 40 engaging and shaping the curved end portions of the shoe upper at the welt, and plates having curved edges adapted to engage and shape the curved side portions of the shoe upper at the 45 welt.

11. A pre-welt shaping machine comprising a support for a pre-welt shoe upper, flexible shaping devices having curved portions for simultaneously 50 engaging and shaping the curved end portions of the shoe upper at the welt, plates having curved edges adapted to engage and shape the 55 curved side portions of the shoe upper at the welt, a system of levers for operating said shaping devices, and manual mechanism other than said levers for operating said plates.

12. A pre-welt shaping machine comprising inflexible members for engaging and shaping the curved side portions of a pre-welt shoe upper 60 mounted on a last, flexible loops curving around and simultaneously engaging the curved end portions of said shoe upper, mechanism for operating said inflexible members to engage and shape said side portions of said shoe upper at the welt between said loops and the welt, means for holding said mechanism in its operated position, and mechanism for operating said loops.

13. A pre-welt shaping machine comprising inflexible members for engaging and shaping the curved side portions of a pre-welt shoe upper 70 mounted on a last, flexible loops curving around and simultaneously engaging the curved end portions of said shoe upper, mechanism for operating said inflexible members to engage and shape said side portions of said shoe upper at the welt between said loops and the welt, means for holding said mechanism in its operated position,

- mechanism for operating said loops, and means for supporting pre-welt shoe uppers of different sizes in position for shaping operations of said members and said loops.
6. 14. A pre-welt shaping machine comprising a support for supporting a last having thereon a pre-welt shoe upper in position in which the welt and the sole of the last are exposed upwardly, flexible loop devices having curved portions engaging and simultaneously shaping the curved end portions of the shoe upper at the welt, inflexible shaping members for engaging and shaping the curved side portions of the shoe upper at the welt, mechanism for operating said members to engage and shape the side portions of the shoe upper at the welt, and other mechanism for operating said devices to shape the curved end portions of the shoe upper at the welt.
10. 15. A pre-welt shaping machine comprising a support for supporting a last having thereon a pre-welt shoe upper in position in which the welt and the sole of the last are exposed upwardly, a lever pivotally supported beyond one end of the shoe upper and last mounted on said support, a flexible loop device adapted to extend along the sides and engage the curved end of the shoe upper adjacent to the welt opposite from said lever, and mechanism for operating said lever to tighten said loop against the shoe upper and thereby shape the shoe upper at the welt in conformity with said last.
15. 16. A pre-welt shaping machine comprising a support for supporting a last having thereon a pre-welt shoe upper in position in which the welt and the sole of the last are exposed upwardly, a lever pivotally supported beyond one end of the shoe upper and last mounted on said support, a flexible loop device adapted to extend along the sides and engage the curved end of the shoe upper adjacent to the welt opposite from said lever, and mechanism for operating said lever to tighten said loop against the shoe upper and thereby shape the shoe upper at the welt in conformity with said last.
20. 17. A pre-welt shaping machine comprising a support for supporting a last having thereon a pre-welt shoe upper in position in which the welt and the sole of the last are exposed upwardly, a lever pivotally supported beyond one end of the shoe upper and last mounted on said support, a flexible loop device adapted to extend along the sides and engage the curved end of the shoe upper adjacent to the welt opposite from said lever, and mechanism for operating said lever to tighten said loop against the shoe upper and thereby shape the shoe upper at the welt in conformity with said last.
25. 18. A pre-welt shaping machine comprising means for supporting lasts of different sizes having thereon pre-welt shoe uppers of different sizes with welts in connection therewith, loops for engaging the opposite curved ends of the shoe uppers on said lasts, mechanism for operating said loops simultaneously to engage and shape the curved end portions of the shoe uppers at the welts, and means for releasing said loops.
30. 19. A pre-welt shaping machine comprising means for supporting lasts of different sizes having thereon pre-welt shoe uppers of different sizes with welts in connection therewith, loops for engaging the opposite curved ends of the shoe uppers on said lasts, mechanism for operating said loops simultaneously to engage and shape the curved end portions of the shoe uppers at the welts, plates operative to engage and shape the side portions of the shoe uppers at the welts in conformity with the curvature of the lasts, and mechanism for operating said plates to engage the side portions of the shoe uppers at the welts between said loops and the welts.
35. 20. A pre-welt shaping machine comprising supporting means for a pre-welt shoe upper, flexible devices arranged to engage simultaneously the opposite curved end portions of the shoe upper at the welt, mechanism for simultaneously operating said devices, a pair of substantially inflexible shaping members operative to engage and shape the inwardly curved side portions of the shoe upper at the welt, and a lever connected with said pair of shaping members for operating the same.
40. 21. A pre-welt shaping machine comprising a support for a pre-welt shoe upper, flexible shaping devices having curved portions for simultaneously engaging and shaping opposite curved end portions of the shoe upper at the welt, plates having curved edges adapted to engage and shape the curved side portions of the shoe upper at the welt, a lever, and connections from said lever for operating said plates.

CARL GEORGE DEUBEL.
